UNITED STATES PATENT OFFICE.

GEORGE REIN, OF BALTIMORE, MARYLAND.

APPARATUS FOR PRINTING FROM NEGATIVES ONTO SENSITIZED SURFACES.

Application filed February 13, 1925. Serial No. 8,876.

My invention relates to an apparatus for printing from a negative onto sensitized surfaces.

Among the objects of my invention are:

- 5 To produce an apparatus for printing from a negative onto a sensitized surface, comprising a vacuum frame so constructed and arranged that a high degree of intimate contact is secured between the negative and the sensitized surface, through the obtainment of a practically perfect vacuum therebetween, and by means of which all unauthorized light rays are completely prevented from reaching said surface.
- 10 15 To produce an apparatus of the character described which is so constructed that the time required for the setting-up operation is materially reduced.

To produce a vacuum frame of the character described having means for readily adjusting the negative in proper register position, thereby assuring the symmetrical printing of the design from the negative onto the sensitized surface, irrespective of any asymmetrical position of the design on the negative.

My invention has special application to the so-called "step and repeat" machines which are utilized in the art to effect repeat designs from a negative onto a sensitized metallic plate, such as zinc, secured in the machine in any approved manner. The negative is supported in a suitable holder provided with sealing means and after being placed in proximity to the desired portion of the sensitized plate, a vacuum is created in the space, included between the sealing means and the surfaces of the negative and the plate in order to produce an intimate contact of said surfaces. The design on the negative is then transferred to the plate by exposing the former to rays from a suitable light source, after which the vacuum is released and the negative stepped along to the next succeeding portion of the sensitized surface.

The advantages of the foregoing method have long been recognized in the art, but considerable difficulty has been experienced heretofore in obtaining a satisfactory vacuum, even after laborious and time consuming efforts to that end, and in excluding er-

rant light rays. The former, to a high degree, is absolutely necessary for effecting an unblurred transfer of fine designs, through achieving an intimate contact of the negative and plate surfaces. I have ascertained that by my arrangement of the sealing means, a nearly perfect vacuum can be obtained without consuming more time than is usually required for placing the negative in its register position.

The exclusion of light rays, other than those which pass through the negative, is an additional requirement of an efficient vacuum frame, as noted above. Stray light rays produce streaks across the sensitized plate when the negative is moved to its next succeeding printing position. These rays are usually due either to a faulty sealing arrangement or they leak through the holes occupied by the bolts securing the negative clamps. These defects are completely eliminated through the use of my invention.

A further disadvantage of vacuum frames now in use is their inability to readily place in register position, a negative on which the design is slightly asymmetrical relative to the negative. If not adjusted, such a design, when transferred to the plate, will appear in a canted position, inasmuch as the negative holder proper is asymmetrical with respect to the plate. By my improved holder, however, I am enabled to quickly register a negative, having a design placed askew, without sacrificing the vacuum required for effective printing or permitting the influx of errant light rays.

My invention also comprises a means for printing onto a portion of a sensitized surface which is smaller in area than that enclosed by the printing frame. Under present operating conditions, the support for the negative is of a fixed size and it therefore follows that, when the design occupies a relatively small portion of the negative surface, not only is great difficulty experienced in placing the negative in proper register position, but also in obtaining an effective vacuum, particularly when the negative extends beyond the edge of the sensitized surface. Unauthorized light rays are also a further disturbing factor. According to my invention a plurality of negative holders are pro-

vided, each of which is adapted to carry a negative of one size, all of said holders differing in size. Said holders are so constructed that they may be nested one with the other, the whole assembly being mounted on a suitable frame which is carried in any approved manner by the machine to which reference has heretofore been made. Therefore, it is possible by my method to select a negative commensurate with the size of the design to be transferred, mount the same in its holder, secure the latter to a holder of the next larger size, said last named holder being then mounted in a holder of the next larger size, this assembly being continued until the base frame is reached. The negative is by this method not only positively held relative to the sensitized surface, but it is also obvious that the problem of obtaining an effective seal is comparatively simple, due to the small area enclosed.

All of the foregoing advantages have been incorporated in a vacuum frame in which a negative may be mounted and an effective seal obtained in a time not greater than that necessary for placing the negative in register position. This result has been achieved by a new arrangement of the negative, the sealing members and the means for securing the negative. My invention is not limited for use with the machines above noted, but possesses general application in the art of contact printing as will become more apparent hereinafter.

These and further objects of my invention will be set forth in the following specification, reference being had to the accompanying drawings, and the novel means by which said objects are effectuated will be definitely pointed out in the claims.

In the drawings:—

Fig. 1 is a plan view of my improved vacuum frame for use in connection with the printing from negatives smaller than the size normally mounted in said frame.

Fig. 2 is a section along the line 2—2 in Fig. 1 looking in the direction of the arrows.

Fig. 3 is an enlarged view of a portion of Fig. 1 showing the means for adjusting a negative on which the design has been placed asymmetrically.

Fig. 4 is a section along the line 4—4 in Fig. 3 looking in the direction of the arrows.

Fig. 5 is a view similar to Fig. 4, but showing the negative mounted on the next larger holder in size.

Fig. 6 is a view of a portion of Fig. 1 looking in the direction of the arrow 6 and showing the relation between the abutting edges of the negative clamps.

Fig. 7 is a perspective view of a portion of a negative clamp.

In the drawings:

10 represents a negative holder frame which is provided with an opening 11 of any convenient form and with a plurality of holes 12 adjacent the edges of said opening. If my improved apparatus is used in connection with a step and repeat machine, said frame will be supported upon the horizontally and vertically movable carriage and appropriate means will also be provided for securing the sensitized plate, hereinafter referred to, in such a manner as to cooperate with the negative mounted in said frame in the usual manner. However, it is not required that my apparatus be used with the foregoing machine for adequate results may be obtained in the general art of contact printing and in such cases, the frame 10 may or may not be employed as desired.

A negative holder 13 provided with a flange 14 is mounted on the frame 12 and said flange is provided with a plurality of holes 15 each of which register with a corresponding hole 12 in the frame 10. Bolts such as 16 secure said holder and frame together. The holder 13 is provided with an opening 17 similar to the opening 11, but smaller than the latter and with a channel 18 adjacent the edge of said opening for a purpose hereinafter explained. The channel 18 is formed in the holder 13 between the edges of the opening 17 and a plurality of holes 19. Said holder is adapted to secure a negative of one size in a manner hereinafter explained.

A negative holder 20 provided with a flange 21 is mounted within the opening 17 of the holder 13, said flange extending under the main body portion 22 thereof. A plurality of holes 23 is formed in said flange, each of said holes registering with a hole 19 in the holder 13. Bolts such as 24 provided with the nuts 25 serve to clamp the holders 13 and 20 together, but as the diameter of the hole 19 is larger than the diameter of the body of the bolt 24 for a purpose hereinafter explained, said bolt is provided with an enlarged portion 26 closely fitting the hole 19, thereby preventing any play of said bolt in said hole.

The holder 20 is provided with an opening 27 which is smaller than the opening 17 and with a channel 28 adjacent the edges of said opening, similar to the channel 18. Said channel is formed in the holder 20 between the edges of the opening 27 and a plurality of holes 29. A negative 30 rests on the top surface of the holder 20, as viewed in Fig. 2, being partly cushioned by a strip of yielding or flexible material 31 which may be rubber, leather or the like. Said strip also serves as an auxiliary seal in obtaining the vacuum hereinafter referred to.

Said negative carries any desired char-

acter of design on its surface and is positioned on the holder 20 so that said design will register with the opening 27. As viewed in Fig. 1 the negative 30 is rectangular in shape, but it is obvious that it may be of any required profile, the shape of the holder 20 being then changed to suit. The negative 30 is provided with a bevel surface on its edges as at 32 and a strip of sealing material, preferably of rubber such as 33, is placed against said surface and extends completely around said negative.

In order to secure the negative 30 against unauthorized movement relative to the holder 20 and to effectively seal the strip 33, I employ the clamps 34 and 35, the former coacting through the strip 33 with the long and the latter in the same manner with the short sides of said negative and coextensive therewith. The clamps 34 extend beyond the end edges of the clamps 35 for a purpose hereinafter explained.

A recess 36 is cut in the underside of each of said clamps to form the relatively narrow shoulder 37 which rests on the top surface 38 of the holder 20. Due to the slight width of the shoulder 37, each of the clamps 34 and 35 is capable of a rocking action relative to the holder 20 and is therefore in effect substantially pivoted thereon. Said clamps are further provided on the edges adjacent to the negative 30 with the surface 39 which contacts with the sealing strip 33 and is angularly disposed to the surface 32 for a purpose hereinafter explained.

Studs such as 40 are mounted in the clamps 34 and 35 in positions to be concentric with the holes 29 in the holder 20 when said clamps occupy their normal position, the diameter of said studs being less than the diameter of said holes. Nuts 41 are mounted on the ends of said studs and serve to lock said clamps in any desired position.

A channel 42 is formed in the clamps 34 and 35 and a sealing strip 43, preferably of rubber is mounted therein, said strip being adapted to cooperate with the sensitized plate 44 to effectively seal off the desired portion of the same. As shown in Fig. 2, the surface of the negative 30 is but slightly below the surface of the sensitized plate 44 and therefore when a vacuum is created in the space included between said surfaces and the strip 43, the plate 44 being pliable will be moved into intimate contact with the surface of the negative. This movement is also facilitated by the yielding quality of the strip 43.

A duct 45 is provided in the clamp 35 and said duct communicates with a nipple 46 secured to said clamp and extending through an opening 47 in the holder 20, the diameter of said opening being greater than the diameter of said nipple for a purpose hereinafter explained. Said nipple is to be

connected to any suitable means for exhausting the air from the space included between the negative and the sensitized plate.

The operation of my improved apparatus is as follows:

Assuming that the elements have been assembled as shown in Fig. 2 for the purpose of transferring a design from a negative whose size is smaller than the normal capacity of the vacuum frame, as exemplified by the size of the holder 18, said assembly is then moved into position opposite the sensitized plate 44 and the sealing strip 43 placed in contact therewith, thus enclosing the desired portion of said plate. The air is then exhausted from the space included between the surfaces of the negative 30, the sensitized plate 44 and the strip 43, thus causing said plate to be moved into intimate contact with said negative under the influence of atmospheric pressure. Light rays are then admitted through the negative from any suitable source, said rays passing through the opening 27 in the holder 20.

According to my method therefore, it is unnecessary to print small designs from large negatives with the attendant difficulties of accurately positioning said negative, securing an effective vacuum and excluding all unauthorized light rays. The method of nesting a plurality of negative holders until a holder is reached, capable of securing a negative whose size is commensurate with the design to be transferred, renders comparatively simple the solution of the foregoing problems, as is apparent in the drawings.

My invention also comprises novel means of clamping the negative 30 in position and of securing an effective seal between said negative and clamps. After said negative has been placed on the top surface 38 of the holder 20, it is obvious that the same may be moved into a plurality of positions until placed in proper register position, due to the freedom of movement of the studs 40 in the holes 29 and of the nipple 46 in the hole 47. This facility of adjustment is particularly advantageous when the design has been placed on the negative in an asymmetrical position, an exaggerated condition of which is illustrated in Fig. 3, the outline of the design being represented by the dotted line 48. Therefore, by my construction, it is merely necessary to move the negative 30 into the register position, place the clamps 34 and 35 adjacent the edges thereof and lock the same in position by tightening the nuts 41.

When said nuts are tightened, said clamps are substantially pivoted about the shoulders 37 and, due to the relative angularity of the surfaces 32 and 39, the interaction of said surfaces causes a wedging or crowding of the sealing strip 33 thereagainst and effectively sealing the passage therebetween. At

the ends of the short clamps 35, a bevel surface 49 is formed which bears the same angular relation to the abutting surface 39 of the long clamp 34, as does the latter to the bevel surface 32 of the negative 30, thus sealing off this portion of the clamps within the sealing strip 43. It is obvious that the provision of a sealing strip between the clamps and negative, which is coextensive with the lateral edges of the negative, is much more effective for the purpose of obtaining a satisfactory vacuum than clamps which bear directly on the negative, the latter resting on the sealing strip. Such has been the means used heretofore in the art, as has also means of securing the negative comprising a plurality of separated clamps. When the negative rests on a strip on which primary dependence is placed for obtaining a vacuum, irregularities in the surface of said negative are not properly filled by said strip, because the pressure exerted by the clamps must act through the negative which is a rigid body. Air leaks therefore occur and an effective vacuum cannot be maintained without the necessity of great labor in providing auxiliary sealing means, such as patches and the like. Further, the provision of separated clamps with the resulting inequalities in the stresses set up within the negative sometimes cause a cracking of said negative from the heat generated by the passage of light rays therethrough. It is obvious that my construction of providing a yielding sealing means between the clamps, which cooperate with the negative throughout their length, and the negative is a marked advance over the means used heretofore.

In Fig. 5 is illustrated the mounting of a negative 50 on the holder 13, said negative being larger in size than the negative 30. As the means for holding said negative in position are identical except as to size with those already described, the same will not be discussed in detail. An opening 51, similar to the opening 47, is formed in said holder for the passage therethrough of a nipple (not shown) for exhausting the air from the space above the negative 50.

While I have shown one form of my apparatus and one means for effecting my improved method, I do not desire to be limited to the exact combinations and manner shown, for many changes may be made therein without departing from the spirit of my invention.

I claim:—

1. The combination with a holder adapted to secure a negative of one size for printing therefrom onto a sensitized surface, of means for securing a negative of predetermined smaller size for printing on said surface, said means being coextensive with the edges

of said smaller negative, means for sealing off the space included between said surface and said smaller negative, and a duct for exhausting the air in said space whereby the portion of said surface bounding said space is forced into engagement with said smaller negative. 70

2. The combination with a holder adapted to secure a negative of one size for printing therefrom onto a sensitized surface, of detachable means for securing a negative of predetermined smaller size for printing on said surface, said means being coextensive with the edges of said smaller negative, means for sealing off the space included between said surface and said smaller negative, 80 and a duct for exhausting the air in said space whereby the portion of said surface bounding said space is forced into engagement with said smaller negative. 85

3. The combination with a holder adapted to secure a negative of one size for printing therefrom onto a sensitized surface, of a plurality of nested holders for securing negatives of varying sizes for printing on said surface, each of said holders being adapted to coextensively engage with the edges of the corresponding negative, means for sealing off the space included between said surface and a negative of predetermined size, and a duct for exhausting the air in said space whereby the portion of said surface bounding said space is forced into engagement with said negative. 95

4. The combination with a holder adapted to secure a negative of one size for printing therefrom onto a sensitized surface, of means for securing negatives of varying sizes for printing on said surface comprising a plurality of nested holders, sealing means between the edges of a negative of predetermined size and its corresponding holder and between said holder and the portion of said surface covered thereby, and a duct for exhausting the air from within the sealed off space for causing the engagement of said negative and said portion of said surface. 105

5. In a vacuum frame, the combination of a holder, a negative, means for securing said negative to said holder coextensive with the edges of said negative, yielding means between said negative and said securing means, a second yielding means between said holder and a cooperating sensitized surface, and a duct for exhausting the air from the space sealed off by said yielding means. 110 115

6. In a vacuum frame, the combination of a holder, a negative movable relative to said holder, means for securing said negative to said holder in a plurality of positions coextensive with the edges of said negative, yielding means between said negative and said securing means, a second yielding means between said holder and a cooperating sen- 120

sitized surface, and a duct for exhausting the air from the space sealed off by said yielding means.

7. In a vacuum frame, the combination of 5 a holder, a negative, clamps for securing said negative coextensive with the edges thereof, yielding means between said negative and clamps, the coacting portions of said negative and clamps being adapted to wedge said 10 yielding means when said clamps are tightened, a second yielding means between said holder and a cooperating sensitized surface, and a duct for exhausting the air from the space sealed off by said yielding means.

15 8. In a vacuum frame, the combination of a holder, a negative provided with beveled edges, clamps for coacting with each of said beveled edges to secure said negative and provided with edges angularly disposed to 20 and coextensive with said first named edges, yielding means between each pair of coacting edges, a second yielding means between said holder and a cooperating sensitized surface, and a duct for exhausting the air from the 25 space sealed off by said yielding means.

9. In a vacuum frame, the combination of a holder, a negative, clamps for securing said negative substantially pivotally mounted on said holder in directions normal to the design surface of said negative and coextensive with the edges thereof, yielding means between said negative and clamps, a second 30 yielding means between said holder and a cooperating sensitized surface, and a duct for exhausting the air from the space sealed off by said yielding means.

35 10. In a vacuum frame, the combination of a holder, a negative provided with beveled edges, clamps for securing said negative substantially pivotally mounted on said holder in directions normal to the design surface of said negative and provided with edges angularly disposed to and coextensive with said first named edges for coacting therewith, yielding means between each pair of coacting edges, a second yielding means between said holder and a cooperating sensitized surface, and a duct for exhausting the air from the 45 space sealed off by said yielding means.

50 11. In a vacuum frame, the combination of a holder, a negative, clamps for securing said negative coextensive with each lateral edge thereof, yielding means between said negative and clamps, a second yielding means between said holder and a cooperating sensitized surface, and a duct for exhausting the air from the space sealed off by said yielding means.

55 12. In a vacuum frame, the combination of a holder, a negative, means for securing said negative to said holder in an asymmetrical position relative thereto, said means being coextensive with the edges of said negative, yielding means between said negative and said securing means, a second yielding means

between said holder and a cooperating sensitized surface, and a duct for exhausting the air from the space sealed off by said yielding means.

60 13. The combination with a holder adapted to secure a negative of one size for printing therefrom onto a sensitized surface, of a plurality of nested holders for securing negatives of varying sizes for printing on said surface, each of said holders being adapted to asymmetrically secure a selected negative to a holder of corresponding size, means for sealing off the space included between said surface and said selected negative, and a duct for exhausting the air in said space 75 whereby the portion of said surface bounding said space is forced into engagement with said negative.

75 14. The combination with a holder adapted to secure a negative of one size for printing therefrom onto a sensitized surface, of a plurality of nested holders for securing negatives of varying sizes for printing on said surface, each of said holders being arranged to coextensively engage with the edges of a corresponding negative, yielding means between said corresponding negative and its holder, a second yielding means between said holder and said surface, and a duct for exhausting the air from the space sealed off by 80 said yielding means.

85 15. In a vacuum frame, the combination of a holder, a negative movable relative to said holder, means for securing said negative to said holder in a plurality of positions, means for sealing off the space included between said holder and a cooperating sensitized surface, and a duct for exhausting the air from 90 said space.

95 16. In a vacuum frame, the combination of a holder, a negative, clamps for securing said negative substantially pivotally mounted on said holder in directions normal to the design surface of said negative, means for sealing off the space included between said negative and a cooperating sensitized surface, and a duct for exhausting the air from said space.

100 17. In a vacuum frame, the combination of a holder, a negative, means for securing said negative to said holder in an asymmetrical position relative thereto, means for sealing off the space included between said negative and a cooperating sensitized surface, and a duct for exhausting the air from said space.

115 18. In a printing frame, the combination of a holder, a negative, and clamps for securing said negative substantially pivotally mounted on said holder in directions normal to the design surface of said negative, said clamps engaging coextensively with the edges of said negative.

120 19. In a vacuum frame, the combination of a holder, a negative, means for securing said negative to said holder coextensive with the edges of said negative, yielding means be- 130

tween said negative and said securing means, a second yielding means carried by said securing means for engagement with a cooperating sensitized surface, and a duct for exhausting the air from the space sealed off by said yielding means.

20. In a vacuum frame, the combination of a holder, a negative, clamps for securing said negative coextensive with each lateral edge

thereof, yielding means between said negative and clamps, a second yielding means carried by said clamps for engagement with a cooperating sensitized surface, and a duct for exhausting the air from the space sealed off by said yielding means.

In testimony whereof, I affix my signature.

GEORGE REIN.
